UNITED STATES PATENT OFFICE.

FRANK K. BOWERS, OF BALTIMORE, MARYLAND.

DESIGN FOR A BOX.

SPECIFICATION forming part of Design No. 18,839, dated January 8, 1889.

Application filed December 4, 1888. Serial No. 292,867. Term of patent 3½ years.

To all whom it may concern:

Be it known that I, FRANK K. BOWERS, a citizen of the United States, residing at Baltimore, in the State of Maryland, have invented 5 a certain new and useful Design for Boxes; and I do declare the following to be a full, clear, and exact description of the invention, such as will enable others skilled in the art to which it appertains to make and use the 10 same, reference being had to the accompanying drawings, and to the letters and figures of reference marked thereon, which form a part of this specification.

In the accompanying drawings, Figure 1 is 15 a perspective view of a box constructed in accordance with my design. Fig. 2 is a central vertical section of the same.

As shown in the drawings, the box is open 20 at the top and is cylindrical in outline, having a broad flange at the bottom, and is provided with a cover extending the full depth of the 25 body, which is of similar shape and flaring at the top, the whole presenting the general appearance of a conventional representation of a hat, as shown.

The cylinder A, which forms the interior portion of the box, is cylindrical in form, and is provided at its lower end with a base-piece, B, which base-piece is extended beyond the edges of the cylinder and is fashioned into a 30 rim for the box. The upper end of the cylinder is open, thus permitting its use as a box or receptacle suitable for cigars, tobacco, or other articles.

The cover D, which forms the outside of the 35 box, is open at its lower end, and is of the same shape as the cylinder A, and has the representation of a band on its lower margin.

What I claim to be new is—
The design for a box, as shown in the accompanying drawings.

In testimony whereof I affix my signature in presence of two witnesses.

FRANK K. BOWERS.

Witnesses:

FELIX R. SULLIVAN,
GEO. E. SAVILLE.
